UNITED STATES PATENT OFFICE.

HUGO FRIEDMAN, OF CHICAGO, ILLINOIS.

DESIGN FOR A LIP-RETRACTOR.

52,566.

Specification for Design.

Patented Oct. 15, 1918.

Application filed January 8, 1918. Serial No. 210,938. Term of patent 3½ years.

To all whom it may concern:

Be it known that I, HUGO FRIEDMAN, a citizen of the United States, and resident of Chicago, county of Cook, and State of Illinois, have invented a new, original, and ornamental Design for a Lip-Retractor, of which the following is a specification.

I have illustrated my invention in the accompanying drawings, in which:—

Fig. 2 is a side elevation of the device.

I claim:—

The ornamental design for a lip retractor as shown.

HUGO FRIEDMAN.
